UNITED STATES PATENT OFFICE.

FRANK F. LANDIS, OF WAYNESBORO, PENNSYLVANIA.

DESIGN FOR A PAVEMENT.

No. 39,059.

Specification for Design.

Patented Feb. 4, 1908.

Application filed October 10, 1905. Serial No. 282,218. Term of patent 7 years.

To all whom it may concern:

Be it known that I, FRANK F. LANDIS, a citizen of the United States, residing at Waynesboro, in the county of Franklin and State of Pennsylvania (whose post-office address is Waynesboro, Pennsylvania,) have invented a certain new, original, and ornamental Design for Pavements, of which the following is a specification.

My said design consists in an arrangement of grooves, or depressions in the surface of artificial stone or concrete pavements, or the blocks composing the same, in accordance

with the ornamental pattern shown in the accompanying drawing, and the edges of the blocks are tapered where fitted together in order to form a continuation of said grooves, or depressions, according to said design.

What I claim is:

The ornamental design for a pavement, as herein shown and described.

[L. S.]

FRANK F. LANDIS.
